UNITED STATES PATENT OFFICE.

LOUIS P. KELLER, OF FAIRFAX COUNTY, VIRGINIA, ASSIGNOR OF TWO-THIRDS TO CHARLES R. TALBERT AND GEORGE W. COLDENSTROTH, OF WASHINGTON, DISTRICT OF COLUMBIA.

WRENCH.

SPECIFICATION forming part of Letters Patent No. 767,283, dated August 9, 1904.

Application filed March 11, 1904. Serial No. 197,676. (No model.)

To all whom it may concern:

Be it known that I, LOUIS P. KELLER, a citizen of the United States, residing in the county of Fairfax and State of Virginia, have invented 5 certain new and useful Improvements in Wrenches, of which the following is a specification.

This invention relates to wrenches; and it relates particularly to that class known as 10 "sliding-jaw" wrenches.

The object of the invention is to provide a wrench of such construction that a movable jaw may be adjusted to fit a nut or other object by the pressure of the hand and that when 15 so adjusted the jaw will automatically become rigidly locked, rendered incapable of movement by pressure applied between the jaws, and at the same time be readily moved manually to release a nut or the like or to enlarge 20 the opening between the jaws.

Further, the object of the invention is to provide a wrench of the kind referred to in which the parts shall be of a construction which require in their formation or fitting 25 little or no hand or machine work, thus simplifying and cheapening their construction.

With these objects in view the invention consists of a wrench constructed substantially as hereinafter described and claimed.

30 The invention is illustrated in the accompanying drawings, in which—

Figure 1 is a side view of a wrench constructed in accordance with my invention, showing by dotted lines the parts carried by 35 the movable jaw. Fig. 2 is a longitudinal sectional view of the wrench. Fig. 3 is a transverse sectional view of the wrench on line 3-3 of Fig. 2; and Fig. 4 is a plan view of a section of the shank, showing a modified 40 form thereof.

In the drawings, 1 represents the shank of the wrench, at one end of which is formed or attached the stationary jaw 2, between which and the movable jaw, to be hereinafter 45 described, is confined a nut or the like to be manipulated by the implement. At the other end of the shank is removably attached a

handle 3. The handle may be secured to the shank in any desired way, as by the nut 4, engaging a screw-thread 5 on the end of the 50 shank.

The movable jaw 6, which, with its adjuncts, form the important parts of the invention, will now be described. The jaw proper, 7, corresponds in size and contour to the stationary jaw 2, the abutting faces of the two jaws being preferably slightly roughened, as usual in such devices. The jaw 6 has formed with it a housing 8, the inner face of which adjacent to the jaw 7 is formed with an abrupt incline 55 9, extending outward from the end adjacent to the jaw 7. Arranged within the housing and bearing at one side against the incline 9 and at the other against the shank 1 is a sphere 10, which is preferably of hardened 60 metal. The sphere is normally pressed against the inclined face by a spring 11, which bears at one end against the inner face of the housing and at the other against the sphere. The sides 8 of the housing are each provided with 65 a slot 13, and the size of the sphere is such that when the parts are in place the sphere projects through the slots, allowing it to be 70 grasped by hand from the outside. In order that the sphere may be prevented from becoming displaced by rough use of the wrench or otherwise, the inclined surface 9 and that portion of the shank against which the sphere bears are preferably concave, affording a means 75 for securing the sphere in place, as shown 80 in Fig. 3 of the drawings. The binding of the sphere between the inclined face of the jaw and the shank will ordinarily be perfectly effected when the surfaces with which the sphere contacts are smooth. In some cases, however, 85 it is desirable to roughen the surface of the shank, as shown in Fig. 4 of the drawings, to prevent sliding of the sphere when the movable jaw is to be locked. The housing is provided at each end with a projection, 90 and through each projection is an opening of a size and shape corresponding to the cross-section of the shank. An open space between the projections and the sides of the housing

allows the introduction of the sphere and spring before the shank is passed through the openings in the projections in assembling the parts of the wrench.

- 5 In the use of the device the stationary jaw is placed against a nut or the like and pressure is applied to move the movable jaw into contact with the object. No manipulation of the parts is necessary to effect the moving of the jaw 6 toward the jaw 2, as a pressure exerted on the jaw 6 to this end releases the sphere from binding on the incline 9. As the jaw 6 is moved the sphere is carried with it, and when the jaw abuts against an object 15 the sphere is held against the incline by the spring. A pressure exerted by the use of the tool on the object grasped will at once firmly seat the sphere, and the greater the pressure exerted the more firmly will the jaw 20 be held. To remove the movable jaw from contact with the nut or the like, the sphere is grasped and moved in a direction away from the same, resulting in releasing the sphere from the binding action between the inclined 25 face and the shank and permitting its free movement.

The sphere is located in the line of pressure exerted in grasping an object between the jaws, so that a direct binding action free from 30 any torsional strain is effected between the jaw and the shank.

Having thus described my invention, what I claim as new, and desire to secure by Letters Patent, is—

- 35 1. A wrench comprising a shank, a stationary jaw carried by the shank, a sliding jaw provided with an inclined surface, and a sphere interposed between the inclined surface and the shank, the sphere being arranged in line 40 with the force applied to the movable jaw in

the use of the implement, substantially as described.

2. A wrench comprising a shank, a stationary jaw carried by the shank, a sliding jaw provided with ways for the reception of the shank and with a housing having an inclined inner face, and a sphere arranged between the inclined face and the shank, substantially as described.

3. A wrench comprising a shank, a stationary jaw carried by the shank, a sliding jaw provided with ways for the reception of the shank, and with a housing having an inclined inner face and slotted sides, and a sphere arranged between the inclined face and the shank 55 and projecting through the slots in the sides, substantially as described.

4. A wrench comprising a shank having a concave face, a stationary jaw carried by the shank, a sliding jaw provided with a housing 60 having an inner inclined concave face, and a sphere arranged between the shank and the inclined face and entering the concaves in the respective parts, substantially as described.

5. A wrench comprising a shank having a concave face, a stationary jaw carried by the shank, a sliding jaw having a housing formed therewith, the housing having an inclined grooved face and slotted sides, a sphere arranged in the housing entering the grooves 70 and projecting through the slots, and a spring bearing at one end against the sphere and at the other end against the inner face of the housing, substantially as described.

In testimony whereof I affix my signature in presence of two witnesses.

LOUIS P. KELLER.
